UNITED STATES PATENT OFFICE

160,742

PORABLE RADIO RECEIVER CABINET

Carl Reynolds, Jr., Birmingham, Mich., assignor
to Avco Manufacturing Corporation, Cincinnati,
Ohio, a corporation of Delaware

Application May 15, 1950, Serial No. 9,950

Term of patent 7 years

(Cl. D56—4)

To all whom it may concern:

Be it known that I, Carl Reynolds, Jr., a citizen of the United States, residing at Birmingham, Michigan, in the county of Oakland, have invented a new, original, and ornamental Design for a Portable Radio Receiver Cabinet, of which the following is a specification, reference being had to the accompanying drawings, forming a part thereof.

In the drawings:

Fig. 1 is a perspective view of the front, top, and right side panels of a portable radio receiver cabinet showing my new design as it appears with the cover in a closed position; and

Fig. 2 is a front perspective view of the cabinet with the cover in an open position.

The opposite side of the cabinet is like the side shown, and the back is plain.

I claim:

The ornamental design for a portable radio receiver cabinet as shown and described.

CARL REYNOLDS, JR.
